BOTTOM HOLE WELL SAMPLER

George W. Rusler, Verona, Pa., assignor to Gulf
Research & Development Company, Pittsburgh,
Pa., a corporation of Delaware

Application April 8, 1936, Serial No. 73,385

19 Claims. (Cl. 137—18)

This invention relates to bottom hole well samplers, and it comprises a tubular chamber adapted to be lowered into an oil well and provided at each end with valved units having outwardly closing valves for entrapping fluids in the chamber as they exist in their natural state in the well, valve operating mechanism in the chamber for causing positive operation of the valves, said mechanism including an interlock for preventing operation of one of the valves until the other valve has closed and a dashpot for one or for each of the valves to soften the closing action of the valves; thus avoiding any pressure or volume disturbance of the fluids in the chamber relative to the surrounding fluids in the well by the closure of the valves; and it also comprises means in the chamber for enabling measurement of the pressure of the fluid entrapped in the chamber without change in volume and means for automatically setting the valve interlock and the valves by simply assembling the valve units to the chamber, one of said units being provided with cable supporting means and a trigger mechanism for operating the valves and the other of said units being provided with a maximum recording thermometer, all as more fully hereinafter set forth and as claimed.

It is of importance to acquire accurate knowledge of the physical and chemical characteristics of fluids as they exist in various locations in a pool or formation and as they exist in the flow string of wells in order to solve problems relating to pumping efficiency and the like and in order to predict with a fair degree of accuracy the changes the fluids in the oil pool will undergo throughout the life of the well. It is particularly important to know the quantities and properties of the gas liberated from solution in the oil at various pressures in the formation and in the flow strings of the wells. With such knowledge it is possible to attain high production efficiency in the operation of wells drilled into a particular pool or formation. This knowledge is best obtained by determining the temperature of the fluids as they exist in the formation by lowering a maximum recording thermometer into the formation at different locations, by securing sample quantities of the fluid from the formation and flow strings of wells drilled into the formation as it exists in its natural state except for change in temperature, and by examining the samples so obtained after adjustment of their temperatures to that at which they existed in the formation or well string as recorded by the thermometer.

To accomplish this purpose numerous forms of apparatus have been developed, adapted to be lowered into a well and entrap a sample of the fluid in the pool at the bottom of the well.

With all prior forms of apparatus of which applicant is aware, the sample of fluid upon examination does not accurately duplicate the fluid in the well from which the sample is taken and therefore figures based upon the results of an examination of such sample fluids are unreliable. 5 This is for the reason that the fluid at the bottom of a well, because of its high pressure is in an extremely unstable condition. The gas to oil ratio is apt to change instantly upon sudden jarring of the sample as by a simultaneous snapping shut of the valves of the sampler. Further difficulty has arisen in accurately determining the pressure of the fluid sample since this pressure must be taken without change in volume. This is because the fluid entrapped is composed of 10 both gas and liquid and frequently gas dissolved in liquids, and the gases under the conditions at which they exist do not necessarily obey the ideal gas laws as to pressure and volume.

A further disadvantage of many prior devices 15 is that external valve control rods are troublesome both in assembling and disassembling the sample, and in catching on joints or obstructions in the well tubing during lowering and raising of the device in a well.

It is an object of the present invention to provide a sampling device which shall entrap a quantity of fluid at the bottom of a well in exactly the same physical and chemical conditions as the fluid surrounding the device during entrapment, 20 and which shall maintain the fluid so entrapped under the conditions existing in the well except for temperature changes.

A further object of the invention is the provision of a sampling device in which the valves to 25 sampling chamber are positively closed and pressure or volume disturbance of the fluids during entrapment is reduced to a minimum. This is accomplished by the provision of an interlock in the valve operating mechanism permitting one 30 valve to close completely before the other, and the provision of a dashpot for one or both of the valves to insure softness of the closing operation.

A further object of the invention is the provision 35 of a valve operating mechanism located entirely within the sampler with the exception of the usual operating trigger at the top of the sampler, and which mechanism automatically sets itself to open the valves upon mere assembling of the sampler parts.

A further object of the invention is the provision of means in the wall of the chamber in which the fluid is entrapped enabling measurement of the pressure of the contained fluid without change in its volume.

A further object of the invention is the provision of novel means for securing the sampler to the end of a cable after valves are set, said means also protecting the trigger from accidental operation during transportation of the instrument and during the act of fastening the end of the cable thereto.

A further object of the invention is the provision of a well sampler which shall be inexpensive in manufacture, composed of a small number of parts arranged for unit assemblage and disassemblage and which shall be exceptionally simple and accurate in operation.

Other objects and advantages of the invention will be apparent from the following detailed description read in connection with the accompanying drawings, wherein,

Fig. 1 is a longitudinal sectional view of the top or head portion of the sampler and shows the trigger mechanism and top valve assembly;

Fig. 1—A is a longitudinal sectional view of the middle portion of the sampler and shows the valve interlock mechanism and the arrangement of the pressure diaphragm means for measuring pressure within the chamber;

Fig. 1—B is a longitudinal sectional view of the bottom or lower end of the chamber and shows the arrangement of the lower valve and thermometer well;

Fig. 2 is a view of a side elevation of a lubricator used in introducing and withdrawing the sampler from a well, and shows the sampler in dotted lines;

Fig. 2—A is a vertical sectional view of the messenger supporting and releasing mechanism for the lubricator.

Fig. 3 is an enlarged horizontal sectional view taken along line 3—3 of Fig. 1 in the direction of the arrows;

Fig. 4 is an enlarged, fragmentary, detail sectional view of the trigger mechanism for closing the valves;

Fig. 5 is a detailed perspective view of the trigger;

Fig. 6 is a detailed perspective view of the trigger spring;

Fig. 7 is a detailed sectional view of the valve interlock showing the position of the parts when the valves are in closed position;

Fig. 8 is a horizontal section view taken along line 8—8 of Fig. 7 in the direction of the arrows;

Fig. 9 is an enlarged horizontal sectional view taken along line 9—9 of Fig. 1—A in the direction of the arrows;

Fig. 10 is a reduced, detail longitudinal sectional view taken along line 10—10 of Fig. 9 in the direction of the arrows;

Fig. 11 is a view similar to Fig. 10 but with the cap and diaphragm of the pressure measuring means removed;

Fig. 12 is an enlarged, detail sectional view showing the construction of the valves and valve seats; and

Fig. 15 is a side elevation of the tie shown in Fig. 14 with the cap shown in vertical section.

Fig. 16 is a detail side elevation of the body of the tie shown in Figs. 14 and 15.

Fig. 17 is a side elevation of the member shown in Fig. 16 and

Fig. 18 is a horizontal section taken along line 5 18—18 of Fig. 16 looking in the direction of the arrows.

Referring to the drawings wherein like numerals indicate corresponding parts throughout the several views, the numeral 1 designates the sample receiving or collecting chamber of the instrument provided with upper and lower outwardly closing valves 2 and 3 respectively. These valves are substantially identical in structure and operation, both being of the mushroom type and 15 consisting of valve stems 4 and 5 to which are secured double inverted, frustro conical shaped valve heads provided with annular knife edge projections 6 and 7 for engaging soft aluminum seats 8 and 9 respectively. Each valve is arranged 20 in a unit assembly for attachment to the end of the chamber, the assemblies consisting of coupling members 10, 11 and 12 and 13 respectively. Members 10 and 12 are threaded externally at one end for engagement with the internally 25 threaded upper and lower ends of the chamber as shown. Valve seats 8 and 9, respectively, are held in position against internal shoulders 14 and 15 in members 10 and 12 by the externally threaded ends of members 11 and 13 engaging the internally 30 threaded ends of members 10 and 12 as shown. Valve unit members 11 and 13 are provided with valve stem guides 16 and 17 cast integrally therewith and supported by spiders (not shown) through which are openings 18 and 19 35 respectively, communicating through the valves with chamber 1. The head or top end section 20 of the instrument screws on to the externally threaded end of coupling member 11 and is provided with openings 21, screened as at 22 for passage of fluids through the device as will be later 40 explained.

The trigger mechanism for operating the valves is arranged as a unit on a base or bracket member 23 held in the head by machine screws 24. Projecting from the base are standards 25 extending downwardly to a point adjacent the end of valve stem 4. (Figs. 1 and 3.) The standards support a lever 26 pivotally connected thereto as at 27 and extending across the end of the 50 valve stem. To hold the valve off its seat the lever is normally held against the end of the valve stem by the longer arm of a bell crank 28 which is pivotally carried as at 29 on the base of the trigger mechanism. The short arm of the bell 55 crank extends horizontally to a point beneath a trigger pin or plunger 30 passing through the head and projecting slightly above the top of the head. This pin is arranged for limited vertical movement in the head by the provision of an enlarged portion 31 in counterbore 32. The counterbore is closed at its lower end by a screw collar 33 through which the pin passes. A spring member 34 secured to the trigger base by means of screws 35 engages through its arms 36 with transversely extending lugs 37 on each side of the end of the long arm of the bell crank to maintain the crank in engagement with lever 26 and hold valve 2 open. In this position the short arm of the bell crank engages the lower end of the trigger pin and forces the pin upward through the head of the instrument in position to be struck by a messenger 38 on cable 39 supporting the instrument. The sampler is secured to the end of the cable by passage of the cable through an open- 70 75 77 79 81 83 85 87 89 91 93 95 97 99

ing in the center of the head of the instrument where it is first bent slightly on a large radius about a cam shaped member 40, to avoid creation of superimposed bending stresses in the cable. 5 Member 40 is held in the head of the instrument by a pin or screw 41 and has a small radius hub portion (not shown) on which the cable is subsequently wound. After winding around the small radius hub the cable is passed along a circumferential groove 42 in the head of the instrument to a set screw (not shown) and is wrapped around the body of the screw for final fastening by clamping under the head of the screw.

On the end of valve stem guide 17 for the lower valve 3, a combined dashpot 43 and thermometer well or housing 44 is secured as at 45. The dashpot is adapted to receive the lower end of valve stem 5 and contains a light coil spring 46 which engages the end of the valve stem to normally hold the valve in open position. A small opening 47 in the bottom of the dashpot permits slow leakage of oil from the dashpot during closing of the valve. 48 is a tube containing a maximum recording thermometer held in housing 44 by screw cap 49. The thermometer may be read or observed through window 50 in the tubing after removal from the housing. The lower end of the instrument including the thermometer well or housing is protected by a cap or foot piece 51 which screws on the externally threaded end of valve unit coupling member 13. This foot piece is open at its lower end as at 52 and provided with screens 53 held in position by castellated, externally threaded ring shape member 54. As so far described it will be seen that when the valves 2 and 3 are open and the sampler submerged in fluid in the well the well fluid may pass freely through the length of the entire instrument, entering at the bottom through screens 53 and leaving at the top through screened openings 21.

The valves are forcibly closed by a mechanism hereinbefore referred to as the valve interlock, located in the sample receiving chamber of the instrument. The interlock consists of push rods 55 and 56 arranged to slide, one within the other in a spider supported bearing member 57, secured within the chamber about midway between the valves by means of screws 58. The opposite ends of the rods are carried in spider supported bearing members 59 and 60 respectively which members are force fitted to rest against shoulders 61 and 62 respectively in the chamber. Push rods 55 and 56 are prevented from falling free of the chamber by shoulders 63 and 64 formed by reducing the diameter of that portion of the rods passing through bearings 59 and 60. The end of rod 56 has secured to it by means of a key 65 a tubular extension or sleeve like member 66 which passes through bearing 57 and has fitted to its reduced end 67 against shoulder 68 a spring end retaining collar 69. The end of push rod 55 has a reduced portion 70 having a sliding fit within tubular extension 66 on push rod 56. Shoulder 71 formed on rod 55 by this reduced portion serves as a seat against which second spring end retaining collar 72 is seated and a coil spring 73 positioned between the collars tends to force the push rods apart or in opposite directions. The extreme end 74 of push rod 55 is still further reduced in diameter where it slides in that part of extension 66 in the bearing 57. In order that one of the push rods may move to close its valve prior to closure of the other valve by the second push rod, the top end 75 portion of bearing 57 is enlarged as at 75 and a

series of circular openings 76 are provided in sleeve 66 adjacent the enlarged portion of the bearing for reception of hardened steel balls 77. These balls are of greater diameter than the radial distance from reduced portion 70 to the outer surface of sleeve 66 so that sleeve 66 is held against downward movement by jamming of the balls in the opening against tapered shoulders 78 formed in the bearing at the bottom of the recess. However, push rod 55 may move upwardly to close top valve 2 and in so doing its reduced end portion 74 moves beneath the balls. Coil spring 73 then acts to force the balls through the openings 76 and against end 74 out of contact with the shoulder formed in the recess, thus permitting sleeve 66 to move downwardly carrying the balls with it to close lower valve 3. 79 is a small oil opening in sleeve 66 for lubrication of the interlock and 80 is a retaining washer fitting within enlarged opening 75.

Provision is made for measuring the pressure of the fluid entrapped in the sampler without changing its volume by permanently mounting a pressure diaphragm assembly in the chamber accessible from the outside of the chamber through opening 84. This diaphragm assembly consists of a flanged body member 82 projecting through the opening and secured to the wall of the chamber by screws 83. This joint is best sealed against leakage by soldering or welding or the like. 30 Against the inner surface of opening 84 through the body member a pressure diaphragm 85 is clamped by means of a cap 86. Cap 86 is slightly relieved on its inner side opposite the diaphragm as shown at 87 and is provided with perforations 35 88 for permitting the pressure of the fluid entrapped in the chamber to exert itself against the inner face of the diaphragm. On the inside of body member 82 and electrically insulated from it is a thimble 89 carrying contact screw 90 40 for making electrical contact with the inner face of the diaphragm. This thimble is supported in porcelain 91 or other insulating material held in inside flange 92 on the body member perforated as at 93 to permit pressure to be applied 45 exteriorly to the diaphragm. Access to the contact screw and to the diaphragm through perforations 93 is had by removing the screw plug 94.

For the purpose of describing the operation of the sampler it will be supposed that the sampler has just been emptied of its contents, disassembled, cleaned, and the valve seats renewed. The valves are set in open position during assembly as follows. The lower valve unit is first attached to the chamber 1. Before attachment a blind cap is screwed to the end of valve stem guide 17 in place of the thermometer well 44 so as to hold valve 3 clear of its soft aluminum seat and in its regular open position with respect to this seat. During attachment of the lower valve unit to the chamber 1 the head of valve 3 strikes the lower end of push rod 56 and forces it upward against the action of spring 73 moving the balls 77 in the interlock opposite the enlarged opening 75 in the bearing 57. The upper valve unit with the trigger set as by depressing the plunger or trigger pin 30 with the finger and tilting the head so that lever 26 falls into position against the end of valve stem 4, is then screwed on to the chamber. During attachment the head of valve 2 strikes the end of push rod 55 and forces it downward against the pressure of spring 73 and at the same time reduced end 70 on the push rod forces the balls 77 into the enlarged opening 75 of the bearing and holds them there thus 75

locking the lower valve push rod 56 in upward position. The blind cap may then be removed, the thermometer reset and placed in the well and the well attached to the valve guide in place of the well 5 attached to the valve guide in place of the well. The lower end or foot piece of the instrument is then screwed on to the bottom valve unit. Next, the diaphragm contact screw 90 is adjusted so that it just contacts the diaphragm when the diaphragm is in its neutral position. The cable is then attached and the instrument lowered into a well, to the bottom thereof or to any point in the flow string at which it is desired to take a sample. At this point it may be advantageous to describe one form of apparatus, illustrated in Figs. 2 and 2-A of the drawings, useful in introducing the sampler into a well. This consists of a pipe 95 called a lubricator which is adapted to be screwed to gate valve 96 at the casing head of a well. The lubricator is longer than the sampler and has a branch pipe 97 leading off from the lower end thereof with a pressure gage 98 and a throttle valve 99 mounted therein as shown. At the upper end of pipe 95 a pulley 100 is supported on an arm 101 carried by pipe 95. The end of the cable is guided over the pulley through a stuffing box 102 and down through a messenger 103 concentrically supported in the upper end of lubricator pipe by means of a guide block 104 rigidly secured to the inside wall of the lubricator by stud bolts 105. The messenger is releasably supported in clamping engagement with the guide member by means of hand wheel operated set screw 106. When desirable the messenger may be threaded on and off the cable by passing the cable through a helical slotted opening 107 in the side of the messenger. The end of the cable is secured to the sampler. The sampler is then drawn upward into the lubricator and the lubricator screwed on to gate valve 96. This valve is then opened and the sampler lowered into the well. During lowering of the sampler in the well, the valves being open, well fluid caused by lowering of the sampler or by convection currents or ebullition of gas passes through the sampler. When the desired location for the taking of a sample has been reached the sampler is allowed to remain motionless for a period of some 20 minutes or longer or until the surrounding and contained well fluid reaches a state of uniformity. When it is thought this stage has been reached, the messenger is released from the lubricator by operation of hand wheel 106 and slides down the cable striking the plunger or trigger operating pin 30 to release lever 26 from engagement with the bell crank or trigger and allow spring 73 to force valve 2 closed. Closure of valve 2 as explained releases the balls 77 in the interlock from the shoulders 78 and allows the spring to close valve 3. Closure of valve 3 however is resisted by slow escape of oil from dashpot 43, through opening 47 so that this valve closes slowly. The purpose of this is to provide an interval of time for any pressure or volume disturbance caused in the oil in the sampler by the sudden closing of valve 2 to die out and also to prevent valve 3 from causing an appreciable pressure or volume disturbance due to its own movement. The movement of valve 2 may be controlled by a dashpot and one arrangement for doing this is illustrated in Fig. 13 of the drawings. In this figure the valve stem 4 is provided with an enlarged portion 103, serving as a piston in counterbore 104 formed on valve guide 16. The counterbore is

provided with a small opening 105 for slow escape of oil entrapped by the piston.

After both valves have been closed the sampler is withdrawn from the well, foot piece 51 removed, and the temperature of the well fluid 5 at the point at which the sample was taken noted by reading the maximum thermometer. The sampler is then heated to this temperature and the pressure of the contained fluid measured by connecting the body of the sampler and 10 a volt meter in series in an electric circuit, through electrical contact screw 90 and diaphragm 85. External fluid pressure is then applied to the diaphragm through perforations 93 in body member 82 until the diaphragm is moved 15 slightly to open the electric circuit or break its electrical contact with the contact screw as indicated by the volt meter. The external fluid pressure recorded by a gauge in the pressure line at this instant will be substantially exactly equal 20 to the pressure of the entrapped fluid provided the contact screw just contacts with the diaphragm and does not exercise pressure against the diaphragm to distort it or is not spaced from the diaphragm so that the diaphragm is distorted by the pressure of the entrapped fluid. Under these conditions any difference in pressure between the making and breaking points of the circuit will be caused by the stiffness or rigidity of the diaphragm itself and with a suitable 30 diaphragm will be so small as to be practically indiscernible on the pressure gauge. This is so particularly in view of the fact that current flowing in the circuit is very small and an almost imperceptible movement of the diaphragm serves 35 to rupture the circuit. The pressure recorded under the above conditions will be substantially exactly equal to the pressure of the fluid in the well at the point where the sample was taken.

The sample fluid may then be removed from 40 the sampler for further examination by applying a suitable tool or apparatus to the end of valve stem 5 and forcing valve 3 off its seat.

It will be noted that the valve interlock enables unit construction of the sampler since it, 45 together with the spring, push rods and sampler body portion constitute a "motor" unit from which the valve units may be easily removed and separately assembled and disassembled. This greatly simplifies the construction and operation 50 of the sampler and is important because of the necessity for renewing the soft metal valve seats each time the sampler is used.

In Figs. 14 to 18 inclusive, I have shown a modified form of cable tie which is particularly adapted for use with the sampler. Referring to these figures the numeral 108 designates the head on the top end of the sampler in which the trigger 30 is mounted as before described and to which cable 39 is secured. Head 108 is provided with 60 an extended, externally threaded portion 109 to receive a protecting cap 110 for the tie. The protecting cap projects above the top of the head and has an opening 111 therethrough for passage of the trigger and the cable. This opening is of 65 considerably greater diameter than necessary to receive the cable and trigger but is of smaller diameter than the diameter of messenger 103.

The purpose of this large opening is to avoid swaging or burring of the metal close to the 70 trigger by impact force of the messenger sent down the cable. Swaging or burring of the cap at this point would cause the trigger to bind or stick. With the above construction the impact force of the messenger is absorbed almost entirely 75

by the top of the cap since the trigger itself offers little resistance to the downward movement of messenger and any swaging or burring of the metal of the cap around opening 111 is remote 5 from the trigger and cannot cause the trigger to bind or stick. A further advantage of this construction of tie is that the trigger and valves of the instrument may be set in operative position some distance from the place where the instrument is to be used and before securing the instrument to the end of the cable, and the cap unscrewed partly or until it extends beyond the end of the trigger to shield and protect it from accidental operation. The sampler may be transported and handled in this condition without danger of accidental firing of the trigger. Immediately before using the sampler the cap is screwed down tight to expose the end of the trigger for striking by the messenger.

20 The tie itself is made in head-piece 108 and consists of a relatively large diameter hub member 112 about which the cable is wound for snubbing the line pull on the cable, an annular groove 113 encircling the head below the hub member 25 for receiving the cable from the hub member and a set screw 116 for final fastening of the end of the cable. The set screw and the hub member are positioned in a recess in the side of the head and the cable is passed downwardly 30 to the hub member through an opening in a projection overhanging the recess as shown. A pin 115 eccentrically located in hub member 112 and passing into the head prevents the hub member from turning.

35 In this form of tie as in the construction of tie first described the line pull on the cable is first snubbed by winding the cable about a large radius hub in a plane passing through the length of the cable above the tie and then is further snubbed 40 by passing the cable around the head in the annular groove so that little or no line pull remains to loosen the final clamping at the set screw or fracture the cable where it bends sharply around the screw.

45 What I claim is:-

1. A well sampler comprising a tubular casing, a valve in said casing adjacent each end thereof, said valves forming a sealed chamber with the casing when closed, closure means in the chamber 50 for each of said valves, means positioned in the casing for releasably holding the valves in open position, and means in the chamber operable by a predetermined movement of one of said valves for operating the closure means for the other of 55 said valves.

2. A well sampler comprising a tubular casing, valves adjacent each end of said casing, said valves forming a chamber with the casing when closed, closure means in said chamber for each of said 60 valves, means in the casing for releasably holding the valves in open position, and means in the chamber operable by a predetermined movement of the closure means for one of said valves for operating the closure means for the other of said 65 valves.

3. A well sampler comprising a tubular casing, a valve in said casing near each end thereof, push rods in said casing for operating the valves, each of said push rods being normally fixed against 70 movement, means for actuating the push rods upon their release, means in the casing for releasing one of said push rods and means in the casing operable by a predetermined movement of said released push rod for releasing the other 75 of said push rods, whereby the push rod actu-

ating means is effective to operate one push rod subsequent to a predetermined movement of the other push rod.

4. A well sampler comprising a casing, a portion thereof forming a chamber for the collection of samples, a valve seat at each end of said chamber and valves for said valve seats, push rods in the chamber for seating the valves, the push rods being normally fixed against movement, means for operating the push rods upon their release, the push rods being associated with each other in sliding arrangement, means for releasing one push rod to permit the push rod operating means to move it a predetermined distance with respect to the other rod and means associated with the two rods for effecting release of the other rod upon said predetermined movement, whereby the push rod operating means will then operate to move both push rods to permit them to firmly seat the valves.

5. A well sampler comprising a tubular casing, a valve in said casing near each end thereof, said valves defining a chamber in the casing, push rods in said chamber for closing the valves, said push rods being movable in opposite directions 25 to close the valves, adjacent ends of the push rods being in telescoping engagement, a collar disposed on the end of each push rod, a spring on said push rods adapted to be compressed between said collars to move the push rods in opposite directions and means in the chamber operable by a predetermined movement of one of said push rods for releasing the other of said push rods for movement by the spring.

6. A well sampler comprising a tubular member 35 open at its ends, a valve near each end of said member, said valves when closed being adapted to form a sealed chamber therebetween with said tubular member, means in the tubular member for holding said valves in open position, means in said chamber for closing said valves and means in the chamber including the valve closing means for preventing closure of one of the valves until the other valve has closed.

7. A well sampler comprising a tubular casing, 45 a pair of oppositely disposed valves in said casing spaced apart to provide a chamber therebetween, push rods for closing the valves, a stationary guide for said push rods, the ends of said push rods being slidable one on the other in said guide, shoulders on each of said push rods, a spring on said push rods adapted to be compressed between said shoulders, said spring tending to force the push rods in opposite directions to close the valves, a recess in said guide, a key in one of 50 said push rods adapted to engage the guide at said recess to prevent movement temporarily of said push rod with respect to the guide, and a cut away portion adjacent the end of the other push rod adapted to receive said key upon movement of said rod a predetermined distance, 60 whereby upon such movement the key will leave the recess in the guide and enter the cut away portion on the other push rod and both rods will be free to move under pressure of the spring in 65 opposite directions to close the valves.

8. A well sampler comprising a tubular casing, upper and lower oppositely disposed valves in said casing spaced apart to provide a chamber therebetween, upper and lower push rods in said 70 chamber for closing said valves respectively, a stationary guide in said chamber for said push rods the ends of said push rods being in telescoping engagement, the upper within the lower, in said guide, shoulders on said push rods, a coil 75

spring on said push rods adapted to be compressed between said shoulders, said spring tending to force the push rods in opposite directions to close the valves, a cylindrical recess in said 5 guide surrounding the push rods, transverse circular openings through the outer telescoping end of said lower push rod opposite said recess, hardened steel balls in said openings of a size to project into said recess, a reduced portion on the 10 inner telescoping end of said upper push rod, said reduced portion being adapted to receive the balls upon being moved opposite said transverse openings and to relieve the recess of said balls whereby the lower push rod is held from moving to 15 close the lower valve until the upper push rod has moved a predetermined distance to close the upper valve.

9. A well sampler comprising a tubular casing, valve assembly units adapted for attachment to 20 the ends of said casing, valves and valve seats in said units adapted to form a sealed chamber with said casing when the valves are closed, means positioned in one of said valve assembly units for releasably holding the valve in said unit 25 off its seat, means for resiliently holding the valve in the other unit off its seat, spring motor means in said chamber for closing said valves and means in said chamber operable by a predetermined movement of one of said valves for 30 operating the spring motor closure means for the other of said valves.

10. In combination, a well sampler wherein a sample of well fluid is entrapped under pressure within a valve chamber and means permanently 35 associated with said chamber for determining the pressure of the fluid entrapped therein, said means comprising a pressure-responsive diaphragm in the wall of said chamber, one side of said diaphragm being exposed to fluid pressure 40 within the chamber, an electric contact screw adjustable with respect to said diaphragm to contact therewith, and means for applying external pressure to the other side of said diaphragm to break its electrical contact with said screw 45 whereby the external pressure required to break said contact is substantially equal to the pressure of the contained sample of well fluid.

11. In an instrument designed for actuation subsequent to its being positioned in place and 50 arranged to be suspended in place by means of a cable attached thereto and having trigger mechanism operated by means of a messenger sent along the cable, a protecting cap and messenger stop for said instrument having an opening 55 of less diameter than the diameter of the messenger through which the cable extends and through which the trigger projects when set, the opening being of sufficient size to accommodate both the cable and the trigger and to leave room 60 between them and its edge whereby the messenger may strike the trigger to operate it and then expend its surplus impact force against the cap and any burring of the top or edges of the cap due to impact with the messenger will not 65 interfere with the operation of the trigger.

12. In an instrument adapted to be suspended at the end of the cable and provided with a trigger projecting therefrom and adapted to be operated by a weight sent down the cable, a protecting device for said trigger having an opening 70 through which the trigger passes and means for moving the protecting device on said instrument with respect to the set position of the trigger to expose it above said opening when the instrument is in position for operation by the messenger 75

and to conceal it beneath said opening to guard it against accidental operation when the instrument is not in position for operation.

13. An instrument to be suspended in the well or the like by means of a cable and having trigger mechanism operable by a messenger sent down the cable when the instrument is in position, a guard member threaded to the instrument and having an opening at the top through which the trigger and the cable pass, the threaded 10 connection between the instrument and said guard member being such as to permit extension of the guard member above the top of the trigger to prevent accidental manipulation thereof until the instrument is ready for use. 15

14. A well sampler comprising a tubular casing, valve assembly units adapted for attachment to the ends of said casing, valve and valve seats in said units adapted to form a sealed chamber with said casing when the valves are closed, 20 means positioned in one of said valve assembly units for releasably holding the valve in said unit off its seat, means for releasably holding the valve in the other unit off its seat, spring motor means in said chamber for closing said valves and means 25 in said chamber operable by a predetermined movement of one of said valves for operating the spring motor means for closing the other valve.

15. A well sampler comprising a tubular casing, 30 a valve in said casing adjacent each end thereof, said valves being adapted to form a sealed chamber therebetween when closed, valve tripping mechanism in said casing for one of said valves, valve tripping mechanism in said chamber for the other of said valves and means connecting said valve tripping mechanisms so that upon actuation of one of said mechanisms to trip its valve, the other mechanism is caused to act to trip its valve, and means for closing said valves after release by said tripping mechanisms. 40

16. A well sampler comprising a tubular casing, a valve in said casing near each end thereof, said valves defining a chamber with the casing when closed, push rods for closing the valves, said push rods being movable in opposite directions to close the valves, adjacent ends of the push rods being in telescoping engagement, a collar disposed on each push rod near the ends thereof, a spring on 50 said push rods adapted to be compressed between the collars to move the push rods in opposite directions, means for holding said push rods in retracted position to compress the spring and means operable by a predetermined protracted movement of one of said push rods for releasing the other push rod for movement by the spring. 55

17. A well sampler comprising a tubular casing, a valve in said casing near each end thereof, said valves defining a chamber with the casing for entrapment of a sample of well fluid, rods for each of said valves adapted for movement of the 60 valves to closed position and means, releasable upon a predetermined movement of one of the rods, for holding the other rod motionless during said predetermined movement of the first named rod whereby said second rod is released to close 65 its valve subsequently to the closure of the other valve by the first rod.

18. In a well sampler having a chamber adapted to receive a sample of well fluid and valves at each end of said chamber for entrapment of 70 well fluid in the chamber, means for holding the valves in open position and means for positively closing the valves, said latter means comprising a closure member for each of the valves and interlocking means connecting said members 75

whereby one of the members is held in inoperative position until the other member has moved a predetermined distance to close its valve.

19. In a well sampler having a chamber adapted to receive a sample of well fluid and valves at each end of the chamber for entrapment of well fluid in the chamber, means for holding the valves in open position and means for positively

closing the valves, said latter means comprising a closure member for each of the valves and means connecting said members whereby one of the members is held in inoperative position until the other member has moved a predetermined distance to close its valve. 5

GEORGE W. RUSLER.
